UNITED STATES PATENT OFFICE

108,171

DESIGN FOR A HAT

Gershon Amster, New York, N. Y.

Application December 11, 1937, Serial No. 73,539

Term of patent 3½ years

To all whom it may concern:

Be it known that I, Gershon Amster, a citizen of the United States and resident of the city, county, and State of New York, have invented a new, original, and ornamental Design for a Hat, of which the following is a specification, reference being had to the accompanying drawing, forming part thereof.

Fig. 1 is a plan view of the basic pattern showing my new design.

Fig. 2 is a perspective side view of a hat embodying the pattern shown in Fig. 1.

Fig. 3 is another perspective side view of the hat shown in Fig. 2.

I claim:

The ornamental design for a hat, substantially as shown.

GERSHON AMSTER.
